SOLID LUBRICATING COMPOUND

Charles A. Miller and David A. Smith, Franklin,
Pa., assignors to Valvoline Oil Company, a cor-
poration of New Jersey

No Drawing. Application August 20, 1932,
Serial No. 629,743

5 Claims. (Cl. 87—9)

This invention relates to improvements in solid lubricating compounds and particularly to that class of hard, dense and dehydrated or partially dehydrated lubricating compounds primarily employed for lubricating bearings carrying heavy loads at high speeds, such as the driving journals of railway locomotives, and commonly known as driving journal compounds or greases.

5 Greases of this character have heretofore been manufactured by compounding a mineral oil comprising a viscous hydrocarbon oil such as cylinder stock with materials embodying the higher fatty acids, such as tallow with the glycerol driven off, or a hard, higher member of the fatty acids such as stearic acid; completely saponifying the fatty acid by the use of an alkali such as caustic soda, in an amount slightly in excess of the quantity required for saponification and subjecting the mixture to a high temperature to dehydrate the same, and to agitation to procure homogeneity. The resultant product thus usually comprises an alkaline grease compound containing the said mineral oil and a soda soap, such as sodium stearate with a low percentage of free alkali, and a low percentage of water. It has thus been the practice to produce a finished grease in which the fatty-acid material is completely saponified and the alkali is present in a low degree, as for example, one-half of one percent. When stearic acid is employed in a grease of this type, a material may be produced which comprises a solid, relatively hard, tough and compact grease of dense and fibrous structure, which, when the cake is rubbed with the fingers is somewhat sticky, but does not granulate or permit fragmental particles to be rubbed off, the particles having a very high degree of coherence, and the density and firmness 10 being substantially equal to the average hard soap. This hard, dense and fibrous structure was considered to be desirable because greases that are too soft or capable of being softened by the temperature encountered in service will, in such service, be squeezed out of the journal boxes and lost on the roadway while the said hard, dense fibrous grease with its high melting point of the order of 400° F. or over and its particles with high degree of coherence will maintain its cake form without such excessive softening as to permit the same to be squeezed out of the journal boxes. The high melting point of said grease resists excessive melting by the high temperatures encountered in service, and it was found that when compounded, there is no ten-

dency in the mass of segregation or the formation of oil pockets, but on the contrary, a homogeneous soap-like mass is produced. Furthermore, it was found that the use of stearic acid as the saponifying acid enabled the introduction of a relatively increased percentage of cylinder stock to be added to the lubricant than would be possible, for example, with other fatty oils. It was also found that this grease had increased efficiency over other former greases in use in the bearings of locomotive driving journals, particularly under extraordinary conditions, as for example, when there is such a mechanical irregularity in the mechanism lubricated as to cause excessive heat. We have observed, however, that when such hard, dense grease, composed as aforesaid, of mineral oil and sodium stearate with a slight or other excess of alkali is used under normal operating conditions, with relatively low temperatures for this class of grease, as well as under extraordinary operation conditions, as for example, when relatively high temperatures are reached, there is a loss of the material fed through the perforated plate and this results in a high consumption factor which was heretofore considered necessary because no grease had been developed which met such operating conditions without such loss. It is thought said loss is due to the excessive cohesiveness of the grease or soap particles or to the excessive adhesiveness of said grease to the metal of the journal or to the excessive and unnecessarily high melting point of said grease, or all of said factors, so that while a grease of said type will lubricate under high temperature conditions, it will, under normal conditions of temperature obtaining in service as well as when used in journal boxes that tend to heat, feed onto the bearings too rapidly, either in the form of a paste or in the form of a softened grease. More grease is thus passed through the perforated plate of the journal boxes than is necessary to lubricate the bearings. The particles of pasty or softened grease thereafter drop off the bearings and are lost on the roadway. We have found, in many tests, that the amount of grease passing through the perforated plate and the loss of such grease was very high. It is therefore, an object of our invention to produce a new grease which will reduce both the quantity of grease passing through the perforated plate, and the loss of grease without reducing the efficiency of the lubricant at all temperatures which will be reached in service, and also to produce a new grease, the use of which, in addi-

5 10 15 20 25 30 35 40 45 50 55

- tion to reducing said quantity and loss, will at the same time efficiently lubricate the bearing surfaces and reduce the coefficient of friction and the temperature thereof.
- 5 By our present invention, we have discovered that if, in compounding, we introduce into our new grease a quantity of fatty acid in excess of the quantity which will be saponified by a given amount of soap-making alkali, thus providing in the finished grease such a relatively low percentage of free acid that will not materially reduce the hardness of the grease or lower the melting point below the proper requirements, we are able, under similar service conditions to reduce the coefficient of friction of bearing surfaces lubricated with our improved grease to a degree materially lower than when said former grease is used, and also to greatly reduce both the quantity of grease so lost and the quantity of grease passing through the perforated plate of the journal box. In other words, by the use of our new grease composition, we procure efficient lubrication while the quantity of grease passing through the said plate is greatly reduced, and we consequently save a large part of the quantity of grease which would be consumed if the aforesaid alkaline grease were used in the journal boxes and passed through said perforated plate.
- 10 It has been observed also that while the consumption of the aforesaid highly cohesive alkaline grease in service is excessive at all journal temperatures reached in service, the rise in such consumption up to approximately 270° F. is gradual and uniform, but when said temperature of the surface of the journal reaches 270° F., the rate of consumption of such highly cohesive alkaline grease increases very rapidly and abruptly with any further increase in temperature up to the maximum temperatures reached by said journals. When, however, our new free-acid grease is used in service, the quantity consumed in comparison with said alkaline grease is reduced at all temperatures and such normal increase as occurs due to rise in the temperature of the bearing is gradual and uniform, there being no excessive consumption and no abrupt rise in the rate of consumption at 270° F. or at any higher temperatures of said bearing surface which may be reached in service. We believe, as above indicated, that this superior performance of our new grease is due to the difference in cohesiveness of the particles in relation to each other and/or to the reduced adhesiveness of our new grease to the metal of the bearings.
- 15 It is also our understanding that the use of our new grease causes the passage through said plate of a better and more efficient lubricating film with a consequent great reduction of the percentage of loss of grease. We have been enabled to accomplish this result at varying speeds or revolutions per minute and with varying temperatures, including the relatively high temperatures accompanying high speeds and/or imperfect equipment. The percentage of free acid should preferably be between one-half of one percent and ten percent by weight of our grease, depending on the characteristics of the grease it is desired to compound and upon the characteristics of the materials used in this compound. We have found that when a grease of the character described is produced embodying free acid amounting to five percent (5%), the percentage of loss in use is reduced to a mini-
- 10 mum, and this, of course, will result in great economy. We have found that a grease such as described containing five percent (5%) of free acid will reduce such percentage of loss at speeds varying from 300 to 1000 R. P. M. to an extent which will result in saving of over fifty percent of the quantity of grease heretofore used in lubricating a given bearing. Our invention, therefore, contemplates the preparation of a grease of the character described, which will not only be free from alkali, but which will contain a percentage of free fatty acid, sufficient to accomplish the purpose hereof, which may be on the order of one-half of one percent to ten percent by weight of the finished grease. We thus 15 reduce the excessive coherence of the soap and/or grease particles, also reduce the excessive and unnecessarily high melting point of the grease to the order of 360 to 390° F., and also reduce the coefficient of friction of bearings lubricated with 20 said grease.
- 20 In order more fully to specify the ingredients used in the grease of our invention, we will now proceed to give an example of our preferred grease, it being understood that we do not hereby 25 intend to limit the invention to the particular ingredients mentioned or to the particular proportions thereof specified.
- 25 In the specific example of our invention, a grease capable of being used in locomotive driving journals and the like was prepared with the ingredients or from the formula hereinafter specified, to wit:—
	Percent
Stearic acid	48.00
Cylinder stock oil	44.95

So soon as the reaction is complete, the bulk of the material begins to decrease and descend in the kettle and to pull away from the sides. At this time, the material is a relatively dry, spongey or gummy mass. Heat with agitation is now applied, a temperature of approximately 350° F. being preferred, for the purpose of softening the compound to bring it into a doughy form, in which form it may be caused to flow and be drawn from the kettle. Agitation is preferably continued throughout this period until the compound is removed from the kettle.

The quantity of sodium hydroxide is, in the above formula, measured in relation to the amount of stearic acid so as to provide in the product derived from said formula an excess of acid and in the preferred form of our invention, this excess of acid preferably amounts to, as aforesaid, approximately five (5%) percent of the finished grease and approximately ten (10%) percent of the sodium stearate soap content of said grease.

An average analysis represented by the examination of several samples of the above-mentioned lubricant with substantially the above formula gives the following composition:—

	Percent
Free acidity as oleic	4.81
Soda soap	51.88
Mineral oil	42.71
Water	.60

The above process may be carried out with a single or double pressed stearic acid of light or dark color or with refined stearic acid, but we preferably employ double pressed stearic acid in order to produce a hard grease of suitable melting point. The formula may contain the excess percentage of fatty acid either as stearic acid, oleic acid or other suitable fatty acid, and the free fatty acid in the finished product may consequently be present as oleic, stearic or other suitable acid. We are thus enabled to produce a grease which will have sufficient hardness and density to meet all conditions of service to which it will be subjected, which will have a melting point of the order of 360 to 390° F., which we find, is sufficiently high to take care of all requirements met under service conditions, and we are enabled to incorporate in such hard grease a percentage of mineral oil necessary in conjunction with the free fatty acid and sodium stearate soap to lubricate locomotive journals at all speeds and temperatures encountered in service, and at the same time the use of our improved grease avoids the loss of grease which normally occurs when an alkaline soda soap grease is employed. It will be noted that we substitute for a portion of the mineral oil content of the former grease a percentage of fatty acid which in itself has lubricating value. The addition or substitution of this free fatty acid thus enables reduction of the mineral oil, and enables the feeding to the bearing of the quantities of grease which is necessary to lubricate the bearing with a minimum consumption of grease.

We find that our said preferred form of grease comprises at atmospheric temperatures a solid, greenish-brown, relatively hard and dry grease of fibrous structure, that when the cake is rubbed, rubbings, fragments or granular particles can be readily removed; that the structure of the grease appears to be partly fibrous and partly granular; that said dry fibrous structure is shot or mottled throughout with a myriad of fine oil glob-

ules or pockets composed of free fatty acid and cylinder stock, and which, when ruptured cause the release of the oils and the spread thereof, so as to form bands, streaks or areas in the mass saturated with free oil, and we believe that these more loosely held granules or particles and the occluded globules of cylinder stock and free acid, when the grease is used, reduce or assist in reducing the dryness and toughness of the fibrous mass or body; that the coherence of the 10 particles of the grease for each other is greatly reduced with the result that instead of feeding through the perforated plate in a continuously flowing and fast-feeding paste or softened grease, the particles of grease on the surface 15 adjacent to the perforated plate, having less coherence, feed more slowly therethrough and have time to be converted into an efficient lubricating oil film, and we also believe furthermore, that these oil globules also furnish to the 20 bearing a supply of free oil. We find that the average penetration of the said several samples above mentioned, unworked, approximated ASTM 15 to 20; that the melting points were approximately 384° F.; that the ingredients 25 and qualities of said grease cause it to have greatly increased efficiency in service on bearings of locomotive driving journals, and the like; that the loss of grease will, as hereinabove specified, be effectively reduced, and we have found 30 that in many cases we are enabled by the use of our preferred compound to reduce the loss of grease more than 50%, thus resulting in great economy of grease and in a consequent reduction of the cost of lubrication per mile. 35

It will be understood that instead of providing in the formula an excess percentage of stearic acid as hereinabove specified, a similar low percentage, such as five (5%) percent of any suitable vegetable or animal oil, fat, wax 40 or any suitable organic or inorganic compound, as for example, chlorinated oil, hydrogenated fat, fish, vegetable stearins, and the like, may be introduced into the compound in such manner as to cause such material to be present in the 45 final composition as free fatty acid, free oleic acid or similar fatty oil or in original form. It will also be understood that while we prefer to prepare our soap from well-pressed stearic acid because of its high melting point, and the 50 hardness of the soap produced therewith, various soaps having high melting points may be employed and various fatty oils and/or fatty acids of high melting point may be used for the 55 making of a suitable soap. For example, animal fatty oils, such as tallow and tallow oils, hydrogenated fats, fish and vegetable stearins having a relatively high melting point may be used or a sodium stearate soap may be prepared from tallow provided, however, that in 60 such case the glycerol in the composition be driven off to produce a relatively hard and solid grease. It will, furthermore, be understood that in the grease of our invention we employ a 65 high boiling point and viscous hydrocarbon mineral oil having high flash point and fire test and that we prefer to use a paraffine base cylinder stock having a fire test of approximately 600° F. or over, a flash point of approximately 550° F., and a viscosity (Saybolt) at 210° of approximately 195 sec.

Having described our invention, we claim:—

1. A solid driving-journal lubricant of acid reaction comprising a substantially dehydrated, boiled, hard grease, the aggregate parts of which

are loosely bound together and composed of substantially equal parts of a viscous hydrocarbon mineral oil and a hard soap prepared from an alkali and a higher fatty acid in an amount sufficient to neutralize the alkali and to provide in said grease free fatty acid in a quantity amounting to approximately five (5%) percent of the lubricant.

2. A solid driving-journal lubricant comprising a substantially dehydrated, boiled, hard grease, the aggregate parts of which are loosely bound together and composed of substantially equal parts of a viscous hydrocarbon mineral oil and a hard soap prepared from an alkali and a higher fatty acid in an amount sufficient to neutralize the alkali and to provide in said grease free fatty acid in a quantity amounting to less than ten (10%) percent of the lubricant.

3. A solid driving-journal lubricant comprising a substantially dehydrated, boiled, hard grease, the aggregate parts of which are loosely bound together and composed of substantially equal parts of a hydrocarbon mineral oil and a hard soap prepared from caustic soda and stearic acid in an amount sufficient to neutralize the caustic soda and to provide in the grease free fatty acid in a quantity amounting to less than ten (10%) percent of the lubricant.

4. A solid driving-journal lubricant comprising a substantially dehydrated, boiled, hard grease, the aggregate parts of which are loosely bound together and composed of substantially equal parts of a viscous hydrocarbon mineral oil and a hard soap prepared from an alkali and a higher fatty acid in an amount sufficient to neutralize the alkali, and to provide in said grease free fatty acid in a quantity amounting to less than ten (10%) percent of the lubricant, 10 said lubricant also embodying free oil in the form of globules distributed throughout the mass.

5. A solid driving-journal lubricant comprising a substantially dehydrated, boiled, hard grease, the aggregate parts of which are loosely bound together and composed of substantially equal parts of hydrocarbon mineral oil and a hard soap prepared from caustic soda and stearic acid in an amount sufficient to neutralize the caustic soda and to provide in the grease free fatty acid in the form of oleic acid in a quantity amounting to less than ten (10%) percent of the lubricant.

CHARLES A. MILLER.

DAVID A. SMITH.
